SHOE BUCKLE CONNECTING MEANS

Filed Nov. 1, 1929

HENRY HELFANT,
INVENTOR
BY Victor J. Evans,

ATTORNEY.

WITNESS

M. B. Ford.

UNITED STATES PATENT OFFICE

HENRY HELFANT, OF ARVERNE, NEW YORK

SHOE BUCKLE CONNECTING MEANS

Application filed November 1, 1929. Serial No. 404,129.

This invention relates to improvements in means for attaching buckles to shoes, and its leading object is to provide a simple connector to enable any shoe clerk to attach a buckle to a lady's shoe, and to enable the wearer to change buckles, when so desired.

One of the other objects of the invention is the provision of a simple coupling to secure a buckle to the shoe, by means of a snap button connection.

Another object of the invention is to provide coupling of this character, which will be comfortable on the foot of the wearer.

Other objects and advantages of the invention will be hereinafter specifically pointed out, or will become apparent, as the specification proceeds.

With the above indicated objects in view, the invention resides in certain novel constructions and combinations and arrangement of parts, clearly described in the following specification and fully illustrated in the accompanying drawings, which latter show embodiments of the invention as at present preferred.

In the drawings:

Fig. 1 is a view in perspective showing a shoe provided with a shoe buckle held in place by the improved coupling means.

Fig. 2 is a side elevation on an enlarged scale of a shoe, partly broken away, showing the shoe buckle and connector in section.

Fig. 3 is a detail rear elevation of the coupling device, in its partly coupled position on the bar of a shoe buckle, on an enlarged scale.

Fig. 4 is a similar view showing the socket member of a snap button coupled thereto.

Fig. 5 is a rear elevation of the buckle, showing its holding bar.

Fig. 6 is a detail sectional view of a stud.

Referring to the drawings in detail 5 designates a lady's shoe and 6 an ornamental buckle, designed to be worn over the vamp 45 of the shoe. This shoe may be of any pattern or type, and the buckle may be of any standard construction.

The buckle is, however, provided with a bar 7 rigidly attached to the back thereof, and which is made of a thin and relatively

narrow metal strip. A fabric or soft leather facing strip or layer 8 is placed against the rear face of the buckle, and for this purpose said strip 8 is formed with a longitudinally slotted portion 8a in which the bar 7 is 55 coupled.

This construction is standard. Shoe clerks at the present time attach the buckles to shoes by stitching or other means, and as a considerable volume of shoe sales are made 60 during rush hours, and women customers want their shoes delivered with buckles attached, without delay, this practice inevitably interferes with shoe sales and deliveries, and is not entirely satisfactory to the customers.

My improved connector consists of a coupling yoke 9, which is preferably formed of leather, but may be obviously constructed of other materials. This yoke is die cut to provide a right wing 10 and a left wing 11, and a connecting bar 12. The wings 10 and 11 are substantially circular in shape, and are spaced apart from each other by the connecting portion or bar 12 so that the inner 70 edges 10' and 11' of said wings will be relatively close to each other, being separated from contact a distance less than the width of the holding bar 7 of the shoe buckle. In order that the wings 10 and 11 will fit neatly 80 against the rear side of the buckle bar 7, and in overlapping relation to each other, a curved slot 13 is formed in said yoke 9, which is sufficiently wide to snugly receive the holding bar 7 of the shoe buckle.

Each of the wings is formed with a circular opening or hole 14 and with radial slits 15 formed in the marginal edge of said opening or hole. This provides an opening having an edge which can be easily fitted to the body of a female or socket button member, as 16.

This button socket member is of well known or standard construction and has a socket 16a which is secured in a finishing head 16b, 95 so as to provide an encircling groove 16c between the flanged end of the socket and the marginal edge of the head.

One of the wings of the yoke is forced over this button member, so that the split mar-

ginal edge portion of the opening thereof will enter the encircling groove 16c of the button socket member. The other wing is then forced over the button in a similar manner, so that the button socket member will be coupled to the holding bar of the buckle in the manner shown in Fig. 4. In this manner an ordinary shoe clerk, without tools, may attach a snap button member to a shoe buckle.

10 In order to attach the shoe buckle, thus equipped with one of the members of a snap button set, to a shoe, a snap button stud is secured to the shoe. This stud is preferably made up of a front element 17a, which snaps into the socket of the snap button socket member, and an anchoring element 17b, which consists of a head and a central prong 17c which is adapted to pierce the leather or material of the shoe so that the front element 17a may be forced thereon by hand pressure, and thus rigidly connected to the shoe.

25 The male stud button element remains permanently attached to the shoe. The only part of this stud element which is attached to the inside face of the shoe leather is the very thin head flange of the inner or anchoring element 17b, which is snugly secured against the leather, so that the latter is compressed thereby, leaving the inner face of the head flange of said anchoring element 17b substantially flush with the inner face of the leather.

30 35 With the male stud snap button element attached to the shoe the clerk merely has to snap the snap button socket member on the male stud element, and the buckle is thus quickly and firmly attached to the shoe without causing any discomfort to the wearer 40 of the shoe, and providing a stable support for the buckle.

35 The wearer may have a series of differently fashioned shoe buckles, each equipped with my improved coupling, and may readily detach any buckle from her shoe and attach a different buckle thereto.

45 50 The hereinbefore described construction admits of considerable modification without departing from the invention, therefore, I do not wish to be limited to the precise arrangements shown and described, which are, as aforesaid, by way of illustration merely. In other words, the scope of protection contemplated is to be taken solely from the appended claims, interpreted as broadly as is 55 consistent with the prior art.

I claim as new:—

55 60 65 70 75 80 85 90 95 100 105 110 115 120 125 130

1. The combination with a shoe buckle having a bar attached to its rear side, of a connector yoke having wings disposed in overlapping relation to each other around said bar, and a snap button element having interfitting relation with the wings to hold said yoke coupled to said bar, said wings hav-

ing registering openings therein to receive said element.

2. An attaching device for shoe buckles comprising in combination with a shoe having an upper, and buckle including a bar, said upper having a male fastening element thereon, a flexible yoke carried on said bar and including a pair of wings, which latter are provided with aligned apertures, said latter element holding said wings in attached relation and being provided with a socket to receive said first element for attaching the buckle to the shoe.

70 75 80 85 90 95 100 105 110 115 120 125 130

In testimony whereof I hereby affix my signature.

HENRY HELFANT.
